(57) **CLAIM**

The ornamental design for a medical device electronic connector plug as shown and described.

DESCRIPTION

FIG. 1 is a top plan view of a medical device electronic connector plug according to a first embodiment of the invention.

FIG. 2 is a bottom plan view thereof.

FIG. 3 is a rear elevation view thereof.

FIG. 4 is a front elevation view thereof.

FIG. 5 is a left side view thereof.

FIG. 6 is a right side view thereof.

FIG. 7 is a first perspective view thereof.

FIG. 8 is a second perspective view thereof.

FIG. 9 is a third perspective view thereof; and,

FIG. 10 is a fourth perspective view thereof.

In the drawings, the broken lines are for the purpose of illustrating portions of the medical device electronic connector plug that form no part of the claimed design.
